[57] CLAIM

The ornamental design for a blood spray shield for surgical scissors, as shown and described.

DESCRIPTION

FIG. 1 is a bottom and front perspective view of a blood spray shield for surgical scissors, showing my new design; FIG. 2 is a side view thereof, the opposite side being of mirror-image appearance; FIG. 3 is a top plan view thereof; and, FIG. 4 is a rear view thereof.

The broken line showing of the scissors and hand in FIG. 1 is for illustrative purposes only and forms no part of the claimed design.
